UNITED STATES PATENT OFFICE.

ARTHUR W. SIMMONS, OF TYLER, TEXAS.

LOCOMOTIVE DRIVING-BOX.

1,339,228.

Specification of Letters Patent.

Patented May 4, 1920.

Application filed September 16, 1919. Serial No. 324,098.

To all whom it may concern:

Be it known that I, ARTHUR W. SIMMONS, a citizen of the United States, residing at Tyler, in the county of Smith and State of Texas, have invented certain new and useful Improvements in Locomotive Driving-Boxes, of which the following is a specification, reference being had to the accompanying drawings.

10 This invention relates to certain improvements in locomotive driving boxes, which is so designed as to eliminate the necessity of removing the driving wheels from underneath a locomotive when necessary to renew 15 crown brasses, and also eliminates the necessity of removing the driving box from assembled position on the locomotive when necessary to take up lateral wear, by removing a flange hub liner and applying the desired amount of metal thereto, and it is also 20 an object of the invention to provide a novel and improved device of this general character wherein is eliminated the necessity of expensive machine work and using it in the 25 rough as it comes from the foundry, for attaining the advantages claimed.

In my prior Patent, No. 1,289,562, dated December 31, 1918, I have illustrated, described and claimed a device of the character 30 under consideration which has proven satisfactory, and it is a particular object of the present invention to improve upon the type of device illustrated in said patent, whereby to obtain even greater efficiency and more 35 satisfactory results.

Another object of the invention is to provide a device of this general character with novel and improved means whereby the lubricating cellar can be anchored on the 40 hub side of the box.

Furthermore, it is an object of the invention to provide a device of this general character embodying a sectional flange hub plate and wherein novel and improved means are 45 provided for maintaining the sections of said plate in applied or working position.

The invention consists in the details of construction and in the combination and arrangement of the several parts of my improved locomotive driving box whereby certain important advantages are attained and the device rendered simpler, less expensive, and otherwise more convenient and advantageous for use, as will be hereinafter more 55 fully set forth.

The novel features of my invention will hereinafter be definitely claimed.

In order that my invention may be the better understood, I will now proceed to describe the same with reference to the accompanying drawings, in which:—

Figure 1 is a view in front elevation of a driving box constructed in accordance with an embodiment of my invention, one of the sections of the hub plate being swung outwardly.

Fig. 2 is a view partly in side elevation and partly in section of my improved box as herein embodied.

Fig. 3 is a view partly in front elevation and partly in section of my improved box as herein embodied with the hub plate sections removed.

Fig. 4 is a view in rear elevation with a portion broken away of a section of the hub plate as herein included.

Fig. 5 is a vertical sectional view taken through the box, as illustrated in Fig. 3, with the cellar removed.

Fig. 6 is a vertical sectional view taken through the cellar as herein embodied.

Fig. 7 is a view in top plan of my improved box as herein embodied.

Fig. 8 is a view in side elevation of my improved box with the hub plate section removed and with a portion broken away.

Fig. 9 is an enlarged sectional view taken substantially on the line 9—9 of Fig. 2.

Fig. 10 is a sectional view taken substantially on the line 10—10 of Fig. 9.

As disclosed in the accompanying drawings, my improved box comprises an arch 1 and the walls or side members 2. The opposed faces of the walls or side members 2 adjacent the arch 1 are provided with the transversely disposed shoulders 3 which afford supports for the crown brass 4. The upper face of the arch 1 at substantially the transverse center thereof is provided with the pockets 5 to receive a locomotive spring saddle as is now generally employed and said upper face of the arch 1 is also provided with a well 6 to contain a suitable lubricant. Each of the outer faces of the walls or side members 2 is provided with the lubricating grooves 7 in communication with the well 6 through the ports 8. The arch 1 has also disposed therethrough the ports 9 leading from the well 6 and registering with the ports 9 of the crown brass so 110

that the contacting face of the crown brass may be suitably lubricated.

Fitting between the lower end portions of the walls or side members 2 of the box 5 is a lubricating cellar C which has one end portion anchored to said walls or side members by a pin 10 extending through an opening 11 in the cellar C and through an opening 12 in the lower portion of each of the 10 walls or side members 2. The opposite end portion of the cellar C is provided in its side walls and adjacent the top thereof with an inwardly and downwardly inclined, open slot or recess 14 which is adapted to 15 receive a lug 15 whereby a further supporting means is provided for the cellar C. The lugs 15 are preferably arranged adjacent the outer or hub face of the box and in applying the cellar the same is engaged 20 with the lugs 15 before the pin or rod 10 is applied.

The hub faces of the arch 1 and the walls or side members 2 are flat and unobstructed, except for the vertically disposed and outstanding T-head 16 arranged at the central portion of the arch 1.

The hub liner comprises two sections 17 substantially in duplicate, and the outer side marginal portion of each of said sections is provided with a flange 18. The lower end portion of the flange 18 is continued by a transversely disposed block pocket 19 extending across the adjacent portion of the section 17 while the upper portion of the flange 18 is provided with a lug 20 extending partially along the upper portion of the section 17. The lug 20 is tapered two ways, and has its inner face *a* inclined downwardly and inwardly for co-action with the lug face *b* provided at an end portion of the wall of the box, these being so tapered as to cause the flange hub plate to fit close against the wall of the box and tighten when bolt 30 is so adjusted.

45 In applying a section 17, the lug 20 is first engaged with the upper portion of the arch 1, and with said lug serving as a fulcrum, the lower end portion of the section 17 is swung inwardly so that the block pocket underlies a shoulder 21, which is inclined upwardly and inwardly in a direction transverse of the wall or side member, while the upper face 23 of the block pocket is inclined upwardly and inwardly.

50 The inner edge of the upper portion of the section 17 is provided longitudinally thereof with a groove or channel 24 which engages a side portion or flange of the T-head 16 whereby the upper portion of the section 17 in conjunction with the lug 20 is effectively held in applied position.

55 The upper part of the block pocket 19 is provided with the pocket 25 in which is mounted a block 26, and the upper face 60 of the block pocket 25 and block 26 is in-

clined or beveled to correspond with the inclination of the shoulder 21. The block 26 rests upon a nut or similar member 27 insertible within the lower or base portion of the pocket 25 through a laterally extending opening 28 formed in the lower portion of the section 17. The lower end of the section 17 is provided with an opening 29 communicating with the pocket 25 and through which extends a bolt 30 threaded through the nut 27. The upper or inner end of the bolt 30 engages with the lower face of the block 26 so that upon requisite rotation of the bolt 30, the block 26 is forced upwardly into engagement with the shoulder 21, whereby the lower portion of the section 17 is effectively locked in working position upon the box.

On account of the use of the block 26, it is not necessary that the shoulder 21 be machined, nor is it necessary that the working face of the block be machined, as bolt 30 can be operated to adjust the bolt to compensate for any inequalities of wear. When it is desired to apply a section 17, 90 bolt 30 is removed and the nut 27 forced into the opening 28 to permit the block 26 to drop to its lowermost position and to a position whereby no obstruction is offered to the requisite swinging movement of the section 17.

The opposed faces of the flange 18 of each of the sections 17 and the adjacent face of the wall or member 2 are provided with elongated grooves or recesses 31, each substantially semi-circular in cross section, and which grooves or recesses are in register when the section 17 is in applied position upon the box. 32 denotes an elongated, cylindrical bar or filler of a length less than the length of the recesses or grooves 31, and which bar or filler 32 seats within such recesses or grooves to provide further means for maintaining the section 17 in applied position. The lower end of the bar or filler 32 is beveled, as at 33, to seat within an undercut or dove-tail 34 in the wall at the lower end of the recess or groove 31 in the wall or member 2, whereby said bar or filler is maintained in desired position while the section 17 is being applied.

By having the bar or filler 32 of a length less than the recess or grooves 31, provision is made for the desired relative longitudinal movement of the section 17 and the box 120 when the section 17 is being pulled down to effect the desired engagement of the section with the box.

The inner vertical margins of the outer faces of the walls or side members 2 of the box are also provided with the outstanding solid flanges 35. The flanges 18 and 35 contact with the pedestal in a conventional manner, and the opposed faces 36 of said flanges 18 and 35 are longitudinally curved or 130

rounded so that in practice the box is capable of limited lateral movement, and it is preferred that the faces 36 of the flanges 18 be curved or rounded more than the opposed faces of the flanges 35 thereby materially relieving the flanges 18 of the strain. This lateral movement serves to compensate for the vertical movement of the driving wheel occasioned by a low or high joint in a track, and also materially relieves the top and bottom portions of the flanges 18 and 35 from the strain occasioned by such high and low joints.

From the foregoing description, it is thought to be obvious that a locomotive driving box constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:—

1. In combination with a driving box, a hub plate embodying substantially duplicate sections, each of said sections being provided with a depending lug engageable with the upper portion of the box and operating as a holding means for the upper portion of the section, and means for securing the lower portion of the section to the box.

2. In combination with a driving box, a hub plate embodying substantially duplicate sections, each of said sections being provided with a depending lug engageable with the upper portion of the box and operating as a holding and adjusting means for the upper portion of the section, and means for securing the lower portion of the section to the box, said lug also serving as a fulcrum whereby the section has swinging movement when being applied to or removed from applied position.

3. In combination with a driving box, a hub plate embodying substantially duplicate sections, each of said sections being provided with a depending lug engageable with the upper portion of the box and operating as a holding means for the upper portion of the section, means for securing the lower portion of the section to the box, and additional means common to both of the sections for holding the same in applied position.

4. In combination with a driving box, a hub plate embodying substantially duplicate sections, each of said sections being provided with a lug engageable with the upper portion of the box and operating as a holding means for the upper portion of the section,

means for securing the lower portion of the section to the box, and a T-head carried by the upper portion of the box and positioned between the sections when said sections are applied, said sections being provided with grooves in which the head seats, whereby said head serves as additional means for holding the sections in applied position.

5. In combination with a driving box provided with shoulders at opposite sides of the lower portion thereof, a hub plate embodying substantially duplicate sections, each of said sections having a holding lug at its upper portion engageable with the upper portion of the box, the lower portion of the section being provided with a block pocket underlying a shoulder of the box when the section is in applied position, and means carried by the block pocket coacting with the shoulder for locking the section in applied position.

6. In combination with a driving box provided with shoulders at opposite sides of the lower portion thereof, a hub plate embodying substantially duplicate sections, each of said sections having a holding lug at its upper portion engageable with the upper portion of the box, the lower portion of the section being provided with a block pocket underlying a shoulder of the box when the section is in applied position, the upper face of the block pocket being tapered to correspond with the shoulder on the box, a block fitting within said pocket, and means for forcing the block in engagement with the shoulder of the box for holding the section in applied position.

7. In combination with a driving box provided with shoulders at opposite sides of the lower portion thereof, a hub plate embodying substantially duplicate sections, each of said sections having a holding lug at its upper portion engageable with the upper portion of the box, the lower portion of the section being provided with a block pocket underlying a shoulder of the box when the section is in applied position, the upper face of the block pocket tapered to correspond with the shoulder on the box, a block fitting within said pocket, and means for forcing the block in engagement with the shoulder of the box for holding the section in applied position, the shoulder of the box being inclined upwardly and inwardly, the opposed face of the block being correspondingly inclined.

8. In combination with a driving box, a hub plate embodying substantially duplicate sections, each of said sections having a holding lug engageable with the upper portion of the box and with means coacting with the lower section of the box for locking the section in working position, opposed faces of the section and box being provided with registering grooves when the section is ap-

plied, and a filler seated within said registering grooves to afford additional holding means for the section.

9. In combination with a driving box, a hub plate embodying substantially duplicate sections, each of said sections having a holding lug engageable with the upper portion of the box and with means coacting with the lower portion of the box for locking the section in working position, opposed faces of the section and box being provided with registering grooves when the section is applied, and a filler seated within said registering grooves to afford additional holding means for the section, said filler being of a length less than the length of the grooves.

10. In combination with a driving box provided with side members, a cellar insertable between said side members and provided between the side members and provided adjacent one end and at opposite sides with

recesses, lugs carried by the side members and extending within the recesses of the cellar to support said cellar in position between the side members, and additional means coacting with the opposite end portion of the cellar for supporting the same in applied position, said lugs and recesses being inwardly and downwardly inclined.

11. In combination with a driving box provided with side members, a cellar insertable between said side members and provided with a recess, a lug carried by one of the side members and extending within the recess of the cellar for supporting the same between the side members, said recess having one end open, said lug and recess being inwardly and downwardly inclined.

In testimony whereof I hereunto affix my signature.

ARTHUR W. SIMMONS.
